UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,534, dated December 31, 1889.

Application filed December 6, 1889. Serial No. 332,830. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design comprises a first and second story and an attic story. At the first story is a porch B, which extends for a distance along the front of the residence, wholly around one end, and for a distance around upon the rear of the residence. This porch B, upon the front of the residence, is surmounted with a shed-roof C and upon the side of the residence with a shed-roof D. At the corner of the residence, beyond the shed-roof D, the porch is surmounted with a gable roof E. A flight of steps a leads to the porch B at the front of the residence, and a flight of steps b leads to the porch

at one corner. Between the roofs C D a tower 30 F rises from the first story and continues upwardly at the exterior of the first and second story and the attic story. This tower is surmounted by a conical roof G. At the front of the residence, upon the second story, and 35 surmounting the roof C, is a porch H, which porch is surmounted by a curved roof I. At one side of the curved roof I is a dormer-window J, surmounted by a hipped roof K. At one side of the dormer-window J is a gable 40 roof L, which extends over an extension at one side of the residence.

Rising from the roof D and projecting through the second story is an arc-shaped bay M. To the left of the bay M is a balcony N, 45 which balcony is to the rear of the gable roof E. Surmounting the second story, at the side of the residence and above the roof D, is a curved roof O. Extending from the curved roof O is a dormer-window P, surmounted by 50 a gable roof.

What I claim is—

The design for the exterior of a residence, substantially as herein shown and described.

WILLIAM K. BENEDICT.
